UNITED STATES PATENT OFFICE

156,645

PLANER

Joseph Marcel Marisseau and Rosaire Duval,
Montreal, Quebec, Canada

Application September 15, 1947, Serial No. 141,397
In Canada July 15, 1947

Term of patent 14 years

(Cl. D93—3)

To all whom it may concern:

Be it known that we, Joseph Marcel Marisseau and Rosaire Duval, citizens of the Dominion of Canada, residing in the city of Montreal, Province of Quebec, Dominion of Canada, have invented a new, original, and ornamental Design for Planer, of which the following is a specification, reference being had to the accompanying drawings, forming part thereof.

Figure 1 is a perspective view showing the front, top and one side of a planer embodying our new design; and

Figure 2 is a perspective view showing the rear, top and other side thereof.

We claim:

The ornamental design for a planer, as shown.
JOSEPH MARCEL MARISSEAU.
ROSAIRE DUVAL.
